UNITED STATES PATENT OFFICE.

JAMES LYONS, JR., OF NEW YORK, N. Y., ASSIGNOR TO SELF AND LEO H. SCHWAB-
ACHER, TRUSTEES, OF NEW YORK, N. Y.

VARIABLE CONDENSER.

Application filed May 18, 1925. Serial No. 31,056.

This invention relates to improvements in radio apparatus, and more particularly to condensers therefor of the variable type.

The primary object in view is the obtaining of extreme nicety and precision of adjustment.

A further object in view is the compounding of the actuating means for enabling an initial, approximate adjustment and a subsequent refined adjustment.

A still further object is the actuation of the movable element of a variable condenser by control located at any convenient point on a panel regardless of the location of the contained condenser.

With these and further objects in view as will in part hereinafter become apparent and in part be stated, the invention comprises certain novel constructions, combinations and arrangements of parts as subsequently specified and claimed.

In the accompanying drawings,—

Figure 1 is a plan view of a condenser embodying the features of the present invention illustrated in a housing shown broken away with a panel seen in horizontal section.

Figure 2 is a view in side elevation thereof, the housing and panel being seen in vertical section and the panel control being seen in edge view.

Figure 3 is a transverse, vertical section taken on the plane indicated by line 3—3 of Figure 2.

Figure 4 is an enlarged, detail, fragmentary, sectional elevation, the section being taken on the plane indicated by line 4—4 of Figure 3, and looking downward.

Figure 5 is a front elevation of one of the panel controls detached.

Figure 6 is a vertical, central section therethrough, parts being seen in elevation.

Figure 7 is a transverse section taken approximately on the plane indicated by line 7—7 of Figure 6, looking downward.

Figure 8 is a similar section taken on the plane indicated by line 8—8 of Figure 6, looking upward.

Figure 9 is a view similar to Figure 3 of a slightly modified embodiment.

In radio receiving apparatus, as is well known, it is important for clarity of reception that as nearly as possible the exact condenser effect be obtained. The import-

ance of the relative shifting of the plates of a variable condenser cannot be exaggerated, and it frequently happens that the wave lengths of sending stations are so nearly alike that a difference of considerably less than one point on the condenser vernier will represent a difference between two stations, and in that instance, with the average commercial variable condenser, the operator merely makes the best guess he can and sets his pointer accordingly, some times using a rubber-tipped pencil to adjust the knob slightly to bring it to the final position. The results are seldom highly satisfactory, and the present invention fully overcomes this difficulty by enabling a far more accurate and much finer adjustment than possible when a pointer and ordinary vernier graduation are depended upon.

Referring to the drawings by numerals, 1 indicates any ordinary housing for radio apparatus having the usual front or instrument panel 2. The present improved condenser is mounted relative to said housing and panel, and consists of fixed and movable leaves, and means for actuating the movable leaves. The condenser parts, including the leaves, may be arranged at any point found desirable within the housing 1, as, for example, in a central portion thereof, while leaving the part adjacent the panel and other side portions free for distribution of other radio receiving apparatus, such as tuning and amplifying tubes, and other well known devices. It is one of the essential advantages of the present invention that the condenser adapts itself to location enabling all of the radio parts to be mounted with greatest facility both with respect to their co-relation and with the assurance of the shortest possible wiring.

Mounted within the housing 1 is the frame 3 for the variable condenser, which frame will be proportioned, of course, according to the size of the condenser, a multiple condenser being illustrated, that is, a condenser made up of a series of independent condensers adapted to be successively switched into operative relation by switches 4, 4, as higher and higher wave lengths are to be received. Each of the units of the condenser is a duplicate of the others. One only, therefore, will be specifically described, and the same reference numerals and de-

scription will apply to the others. While three units are shown, as many may be utilized as required. Also, it will be obvious that the number of plates illustrated may be varied for each unit to any extent found desirable without the slightest departure from the scope and intent of the invention.

The frame 1 is divided into as many compartments as there are condenser units, and within each compartment are fixedly mounted a series of spaced condenser plates 5, 5, which are electrically connected in the usual manner. Between each two of these plates is arranged a movable condenser plate 6. The several plates 6 are pivoted, at 7, and carefully insulated from the other plates, one set of the plates being connected to one side of the circuit and the other set to the other side. A cross bar 8 connects the free ends of all of the plates 6, and is pivotally engaged by an arm 9 (see Figure 4) depending from an actuator. The said actuator preferably consists of a slide 10 mounted in and guided by a tube or like guideway 11 curved to conform with the path of travel of the free ends of the plates 6 when swung upon their pivots. The tube 11 is formed with a lateral slot 12, and the arm 9 is formed integral or appropriately fixed to the slide 10, extends laterally therefrom through the slot 12, and is then bent to a position for pivotally engaging the cross bar 8. Thus, shifting of the slide 10 will effect corresponding swinging movement of the several plates 6 engaged by the respective bar 8. The several guideways or tubes 11 may be formed of any appropriate non-metallic substance, and may be otherwise shaped than as tubes, but in tubular form serve effectively to contain and direct the actuating cable 13 which engages the slide 10 and extends longitudinally throughout the guide or tube 11. The guide or tube 11 in each instance extends for a sufficient distance for directing the cable 13, and the cable extends thence to the panel control 14 for the condenser. As seen in Figures 1 and 3, tube 11, after completing its arc conforming to the stroke of the movable plates, loops to direct the cable 13 into a line at right angles to the planes of the movable plates 6, but the said tubes may be otherwise shaped when the condenser is otherwise located relative to the panel, as, for instance, as seen in Figure 9, and as will be hereinafter mentioned. Any position whatever of the controls 14 is possible with this arrangement, different in location merely requiring the appropriate shaping of the tube or guideway 11. The cable 13 is preferably a non-conducting cord, but may be of any appropriate material. In this structure also, gravity is depended upon for the return of the plates 6 to position between plates 5, but provision may be made for positive return when desired after the manner

indicated in Figure 9 as will be hereinafter described.

It will be apparent that the several plates 6 will assume that relation to the plates 5 afforded by the location of the slide 10, which may be adjusted to a nicety by the panel control 14, as seen in detail in Figures 5 to 8 inclusive. Each panel control for a condenser unit is a duplicate of the others, and but one is, therefore, illustrated and will be described in detail. The panel control consists of an elongated housing adapted to be anchored to the face of the panel and having an elongated slot 15 through which extends the thumb piece 16 of a block 17 carried by a slide 18 mounted and adapted to slide within the housing, a part of the slide 18 extending into the slot 15 and being guided therein. The sides of the wall of the housing along the longitudinal edges of slot 15 are preferably graduated, and the thumb piece 16 preferably terminates in pointers 19, 19, adapted to cooperate with said graduations. The said graduations take the place in this apparatus of the vernier graduations of the ordinary commercial variable condenser. The slide 18 is hollowed out and formed with an elongated slot-like recess 20 for accommodating the block 17, so that the block may be shifted along and within the slide 18 independently of any movement of the slide itself. To facilitate this independent shifting of the block 17, the block is mounted preferably on a screw-threaded spindle 21 arranged longitudinally of the slide 18, and having its ends journaled in the ends of the slide 18. One of the end portions of the spindle 21 extends sufficiently beyond the end of the slide 18 to receive and fixedly carry a knurled head or other appropriate operating handle 22, so that, when the head 22 is revolved, the spindle 21 is likewise revolved, and the block 17 is caused to travel lengthwise of slide 18 independently of any movement of said slide 18. The cable 13 extends through a guiding tube 23 into the housing for slide 18, the tube 23 being bent downward to direct the cable 13 toward said slide 18. The cable extends through the upper end portion of the slide 18 and is fixed to the block 17, an aperture 24 being formed in the upper end portion of the slide 18 for accommodating free longitudinal movement of the cable 13 independently of the slide 18. The slide 18 preferably frictionally engages the surrounding housing so as to remain in any given adjusted position. This friction may be assured by various mechanical apparatus, such, for example, as is illustrated in Figure 7, in which is seen the plungers 25, 25, carried by the slide 18 and stressed by springs 26, 26, so that said plungers constantly frictionally engage the inner surface of the side walls of the housing

for slide 18, and, accordingly, frictionally retain the slide at any point at which it happens to be left.

In operation, the thumb piece 16 is grasped and the slide 18 is thereby shifted up and down for adjusting the plates of the condenser as required for "tuning in". When the operator perceives that he is approximately in the field desired, he discontinues movement of the slide 18. He then begins to rotate the handle or disc 22 for adjusting the pointers 19, as required, of course, correspondingly adjusting the cable 13 and the movable plates 6. A very fine and satisfactory adjustment may thus be accomplished easily and quickly. Where more than one unit of the condenser is utilized, each may be "tuned in" independently of the other, but by the same mode of operation as just stated and with the same satisfactory results. When the operator has once located a station of a given wave length and has a memoranda on the subject, the second time he desires to locate the same, his work is greatly facilitated, but the operation will be practically the same. The extended movement of the plates 6 is accomplished quickly, and then the finer adjustment obtained by the slower method of threading the block 17 to the required position by operation of the disc 22.

The adaptability of the invention to every known form of receiving set should be apparent and the great utility of freedom of location of the parts with assured nicety of adjustment is found effective in every instance. This adaptability extends to the point of location of the condenser otherwise than in the usual horizontal position. For instance, the moving plates may be arranged to swing horizontally instead of vertically in which case they would not drop back by gravity, and I have illustrated in Figure 9 a slightly modified embodiment of the invention in which the structure is otherwise identical but which is especially adapted to enable use of the condenser regardless of its location or of the effect of gravity. In this construction, the usual fixed plates 5' and pivoted plates 6' are employed. The plates 6' are connected by the usual cross bar 8' pivotally engaged by the arm 9' carried by the slide 10' within the guide or tube 11'. The guide or tube 11' in this instance, however, not only extends in an arc upward from the lowermost location of the free end of the plates 6' but also extends downward and a cable 13' engages the slide 10' at one side, and a cable 13'' engages the slide 10' at the other side. The two cables extend one into the upper end and the other into the lower end of the housing 14' at the panel, and the two cables meet at the block 17' which is carried in the slide 18' mounted in housing 14'. The usual threaded spindle 21' en-

gages the block 17' and is provided with the operating knurled disc 22' for enabling the refined adjustment of the cables 13' and 13'' after the main adjustment thereof incident to shifting the slide 18'. 70

Thus it will be seen that the structure seen in Figure 9 parallels in form and function that seen in Figure 3 and described in detail above, except for a slightly different location of the control housing and for the affirmative return motion of the pivoted plates which enables operation thereof regardless of gravity and regardless of positioning of the condenser. 75

It should be observed that the knob attached to an axial shaft of a rotary variable condenser has relatively slight movement. The periphery of the knob travels only a very small fraction of the distance which the periphery of the disc fragments travel. 80 Therefore, the vernier graduations for the needle of the knob must be extremely fine for indicating any substantial degree of fineness of adjustment of the condenser. By contrast, the present invention has its indicator move relative to the movement of the peripheral portion of the moving plate, or more accurately that portion of the moving plate most remote from the axis of the pivot. Therefore, the indicator of each 85 control 14 possesses the capacity for the maximum amount of movement for any given movement of the movable plates, and the graduations on the face of the housing of control 14 are proportionately and relatively magnified while actually offering ample space for refinement of adjustment of the pointer. 90 95

What is claimed is:

1. In variable condensers, the combination of a stationary element and an element movable relative thereto, flexible means for moving the movable element, and means sustained by the flexible means for indicating the extent of movement of the movable element. 100 105

2. The combination with a housing and a variable condenser therein, of a flexible cable connected to the movable element of the condenser and extending to the exterior of the 110 housing. 115

3. In a variable condenser, the combination, with a stationary element, of an elongated element pivoted substantially at one end to swing relative to the stationary element, and flexible means engaging substantially the other end of the elongated element for swinging the same. 120

4. In variable condensers, the combination with a stationary element and an element movable relative thereto, of flexible means for moving the movable element, and a guide for the flexible means directing the same at an angle to the path of movement of the movable element. 125 130

5. In variable condensers, the combination with a stationary element and an element movable relative thereto, of flexible means for moving the latter, and a tubular guide 5 for the flexible means. 70
6. In variable condensers, the combination with a stationary element and a movable element, of a tubular guide disposed adjacent the movable element, flexible actuating 10 means for the movable element arranged in the guide, and rigid means extending from the guide to and engaging the movable element. 75
7. In variable condensers, the combination 15 with a stationary element and a movable element, of a tubular guide disposed adjacent the movable element, flexible actuating means for the movable element arranged in the guide, and rigid means extending from the 20 guide to and pivotally engaging the movable element. 80
8. In variable condensers, the combination 25 with a stationary element, a movable element, of flexible means for actuating the movable element, a guide for the flexible means, a slide carried by the guide and engaged and actuated by the flexible means, and means of connection between the guide 30 and the movable element. 90
9. In variable condensers, the combination 35 with a stationary element and a pivoted element, of a guide extending along the path of movement of the pivoted element, a slide carried by the guide, an arm carried by the slide pivotally engaging the pivoted element, and flexible means engaging the slide for actuating the same. 95
10. In variable condensers, the combination 40 with a stationary element and a pivoted element, of a guide arched to conform to the path of movement of portions of the pivoted element, a slide mounted on the guide, means of connection between the slide and pivoted element for imparting motion from the slide 45 to the pivoted element, and means for shifting the slide along the guide. 100
11. In variable condensers, the combination 50 with a stationary element and a pivoted element, of a tubular guide arched to conform to the path of movement of parts of the movable element, a slide mounted in the guide, the guide having a lateral slot, an arm outstanding from the slide and pivotally engaging the movable element, and means for shifting the slide along the guide. 11
12. In variable condensers, the combination 55 with a stationary element and a movable element, of a slide spaced from the movable element, means flexibly connecting the slide 60 to the movable element for shifting the movable element when the slide is shifted, and means for shifting the slide. 12
13. In variable condensers, the combination 65 with a stationary element and a movable element, of a slide spaced from the movable 130
- element, means connecting the slide to the movable element for shifting the movable element when the slide is shifted, and flexible means for shifting the slide. 10
14. In variable condensers, the combination with a stationary element and a movable element, of an indicator slide spaced therefrom, a slide adjacent and connected to the movable element for shifting the same, and means for transmitting movement from the indicator slide to the second-mentioned slide. 75
15. In variable condensers, the combination with a stationary element and a movable element, of an indicator slide spaced therefrom, a slide adjacent and connected to the movable element for shifting the same, and flexible means for transmitting movement from the indicator slide to the second-mentioned slide. 80
16. In variable condensers, the combination with a stationary element and a movable element, of an indicator actuator spaced therefrom, and flexible means for transmitting movement from the indicator actuator to the movable element. 90
17. In variable condensers, the combination with a stationary element, a movable element, a housing therefor, and a panel spaced from the housing, of an indicator slide disposed exteriorly of the panel, and means for transmitting motion from the indicator slide to the movable element. 95
18. In variable condensers, the combination with a stationary element, a movable element, a housing therefor, a panel spaced from the housing, of an indicator slide disposed exteriorly of the panel, means for transmitting motion from the indicator slide to the movable element, and means movable relative to the indicator slide for further shifting the movable element. 100
19. In variable condensers, the combination with a stationary element and a movable element, of an indicator slide spaced therefrom, a block movably mounted on the slide, and a flexible connection between the block and the movable element for imparting movement from the block or the slide to the movable element. 11
20. In variable condensers, the combination with a stationary element and a movable element, of an indicator slide spaced therefrom, a block slidably carried by the slide, and means for transmitting motion from the slide and from the block to the movable element. 11
21. In variable condensers, the combination with a stationary element and a movable element, of an indicator slide spaced therefrom, a block slidably carried by the slide, means for transmitting motion from the slide and from the block to the movable element, and threaded means for actuating the block. 12
22. In a variable condenser, the combina- 130

- tion, with a plurality of stationary elements and a plurality of elements movable with respect to the stationary elements, of an actuator, and a threaded actuator carried by 6 the first mentioned actuator, and means connecting both actuators to the movable elements, each actuator being adapted to function relative to the other without the necessity for retrograde movement.
- 10 23. In a variable condenser, the combination, with a plurality of stationary elements, a plurality of elements movable relative thereto, of an actuator for actuating the movable elements, and means carried by the 15 actuator for the effecting of fine adjustments of one of the movable elements, the actuator and fine adjustment means being adapted to function relative to each other without the necessity for retrograde movement.
- 20 ~ 24. In a variable condenser, the combination, with stationary elements and elements movable relative thereto, of an actuator flexibly connected with the movable elements for simultaneously moving the same, and independent means for effecting fine adjustments of one of the movable elements, the actuator and fine adjustment means being adapted to function relative to each other without the necessity for retrograde movement.
- 25 30
26. In variable condensing apparatus, the combination of means for indicating movements of the movable element of a condenser, means for moving the indicating means to a general adjustment, and means for moving the indicating means to a refined adjustment, the refined adjustment means having means adapted for indicating the relative calibration of both said adjustments. 35
27. In apparatus of the class described, the combination, with a stationary element and an element movable relative thereto, of flexible means for moving the movable element, and guiding means for the flexible means for directing the same into a path of movement at an abrupt angle to the path of movement of the movable element. 40
28. In apparatus of the class described, the combination, with a stationary element and an element movable relative thereto, of a flexible cable engaging the movable element for moving the same relative to the stationary element, and guiding means for the cable for enabling shifting thereof in a direction different at the place beyond the guiding means from the direction of shifting of the cable at the place approaching the guiding means. 45
29. In testimony whereof I affix my signature.
- JAMES LYONS, Jr.
